UNITED STATES PATENT OFFICE.

GEORGE W. BUFFORD, OF BROOKLYN, NEW YORK, ASSIGNOR TO J. H. WILLIAMS AND COMPANY, OF BROOKLYN, NEW YORK, A CORPORATION OF NEW YORK.

CHAIN WRENCH.

SPECIFICATION forming part of Letters Patent No. 698,794, dated April 29, 1902.

Application filed July 13, 1901. Serial No. 68,155. (No model.)

To all whom it may concern:

Be it known that I, GEORGE W. BUFFORD, a citizen of the United States, residing in the borough of Brooklyn, county of Kings, city 5 and State of New York, have invented certain new and useful Improvements in Chain Wrenches, of which the following is a specification.

The object of the present invention is to 10 make a chain wrench having a "flat" chain which shall be especially useful in turning pipe-fittings, elbows, T's, and short sections of small diameter connecting pipes of larger diameter.

15 A wrench made in accordance with the present invention is so constructed and organized that the pipe or other article to be grasped is squarely embraced between the reversible flat chain on one side and either of the opposing grip-faces on the other.

The present improvements are illustrated in the accompanying drawings, in which—

Figure 1 is a side view showing the wrench in use, only part of the handle, however, 25 being shown. Fig. 2 is a longitudinal section. Fig. 3 is a cross-section on a plane indicated by the line 3 3 in Fig. 2.

Referring to the drawings, A is the handle, B is the head, and C is the chain.

30 Only a portion of the handle A is shown. The head B is secured to the end of the handle in any suitable way. As here shown, the head is formed with a tubular socket a, terminating within near the apex of the head 35 in a screw-threaded recess. The end of the handle has a cylindrical section b, which fits snugly within said socket and at its extreme end has a projecting screw-threaded stud c, which screws into said screw-threaded recess.

40 This construction insures a secure and rigid connection between the handle and the head.

The head is provided with gripping-teeth on its opposite faces d d, and these faces are in line with the handle, so that a medial longitudinal plane passing through the handle bisects the said grip-faces.

45 The head is centrally disposed with reference to the axis of the handle, and each of its grip-faces is continuous from side edge to 50 side edge and extends across the plane of the

handle—that is to say, a central longitudinal plane which passes through the axis of the handle and is parallel with the sides of the head also passes through the grip-faces of the head.

55 The chain C is a flat chain pivotally connected at e to a swivel-block D, which is swiveled to the handle between the base of the head and a shoulder f on the handle, this block turning on the cylindrical section b of 60 the handle. The chain, as shown, is a flat chain composed of similar links, the links being arranged in succession, with a pair of parallel internal links g g lying side by side and a pair of parallel external links h h embracing the links g g and pivotally connected by a cross-pin E, preferably connected immovably (by riveting or endwise compression) with the outer links h h and passing loosely between the inner links g g, which swivel 65 thereon. The terminal link F, connecting the chain and swivel-block, is shown as composed of two of the inner links g g. The pins E E project outwardly on both sides of the chain to constitute projecting locking-studs 70 i i, which interlock with suitable locking provisions G G, carried by the swivel-block at its other end so as to be always diametrically opposite to the chain-pivot. These locking- 75 studs on the chain may be omitted throughout that portion of the chain nearest the pivot-pin E, which can under no circumstances register with the locking provisions G G; but to avoid showing a long section of chain in Fig. 3 said studs are illustrated closer to the said 80 pivot-pin than is necessary in practice.

The locking provisions G G, which co-operate with the studs i i, consist of two projecting ears j j, integral with the swivel-block, provided on their inner sides with suitable 85 locking-recesses adapted to receive the chain-studs when the chain is passed between them. These locking provisions are preferably constructed like those of United States Patent No. 499,508, dated June 13, 1893, so as to prevent the chain from accidentally dropping out 90 when used underneath the handle.

95 When the present improved wrench is used, the chain is passed entirely over the head, so as to embrace the article to be turned squarely 100

between the chain and one of the grip-faces of the head, the chain-studs being then interlocked with the locking provisions on the swivel-block. Owing to the connection of the 5 chain with the swivel-block, the swiveling of said block and the locking provisions being on the swivel-block, the wrench can be used with either grip-face up.

When the wrench is in use, the chain passes 10 from its pivot in contact with the article to be turned, thence over the central head in contact with its apex, and thence in contact with the further grip-face to the locks.

Preferably, as shown, the head is provided 15 with slightly-projecting chain-retaining shoulders k k , between which the chain lies when in use, so that the chain cannot slip laterally off from the head while in use.

I claim as my invention—

- 20 1. A chain wrench having, in combination, a handle having a cylindrical section at one end separated from the rest of the handle by a shoulder and a screw-threaded stud at the outer end of said cylindrical section; a central head composed of a single piece having opposite continuous grip-faces with projecting chain-retaining shoulders at the side edges, said grip-faces extending across the plane of the handle, said head having a cylindrical socket terminating near the apex of the head in a screw-threaded recess, said socket and recess receiving the cylindrical section and screw-threaded stud of the handle; a swivel-block turning on the cylindrical section of said handle between the base of the head and the shoulder of the handle, said swivel-block having on one side a chain connection and on the other side of the handle locking provisions; and a flat chain having 40 locking-studs, said chain being pivoted to said swivel-block on one side and being adapted to be carried over the head in coöperation with the grip-faces thereof and to be locked to said swivel-block locking provisions on the other side of the handle, said head and chain being so related that the article operated upon is grasped squarely between the chain and one grip-face of the head, and the chain comes in contact with the other grip-face.
- 45 2. A chain wrench having, in combination, a handle; a central head having opposite continuous grip-faces extending across the plane of the handle; a swivel-block turning on said handle at the base of the head, said swivel-block having on one side a chain connection and on the other side of the handle locking provisions; and a chain pivoted to said swivel-block on one side and being adapted to be carried over the head in coöperation

with the grip-faces thereof and to be locked 60 to said swivel-block locking provisions on the other side of the handle, said head and chain being so related that the article operated upon is grasped squarely between the chain and one grip-face of the head, and the chain 65 comes in contact with the other grip-face.

3. A chain wrench having, in combination, a handle; a central head having opposite continuous grip-faces extending across the plane of the handle; a swivel-block turning on said 70 handle at the base of the head, said swivel-block having on one side a chain connection and on the other side of the handle locking provisions; and a chain pivoted to said swivel on one side and being adapted to be carried 75 over the head and to be locked to said swivel-block locking provisions on the other side of the handle, said head and chain being so related that the article operated upon is grasped squarely between the chain and one grip-face of the head, and the chain comes in contact with the other grip-face.

4. A chain wrench having, in combination, a handle; a central head having opposite continuous grip-faces extending across the plane 85 of the handle; and a swiveled chain adapted to be carried from one side over the head and to be locked on the other side, said head and chain being so related that the article operated upon is grasped squarely between the chain and one grip-face of the head, and the chain comes in contact with the other grip-face.

5. A chain wrench having, in combination, 90 a handle; a central head having opposite continuous grip-faces extending across the plane of the handle and having projecting chain-retaining shoulders at the side edges; a swivel-block turning at the base of the head, said swivel-block having on one side a chain connection and on the other side of the handle locking provisions; and a chain pivoted to said swivel on one side and being adapted to be carried over the head between the projecting shoulders thereof and to be locked to said 100 swivel-block locking provisions on the other side of the handle, said head and chain being so related that the article operated upon is grasped squarely between the chain and one grip-face of the head, and the chain comes in 105 contact with the other grip-face.

In witness whereof I have hereunto signed my name in the presence of two subscribing witnesses.

GEORGE W. BUFFORD.
